[57] **CLAIM**

The ornamental design for a flashlight head, as shown
and described.

DESCRIPTION

FIG. 1 is a perspective view of a flashlight head showing
my new design;

FIG. 2 is a side elevational view thereof on an enlarged
scale;

FIG. 3 is a front elevational view thereof on an enlarged
scale;

FIG. 4 is a rear elevational view thereof on an enlarged
scale;

FIG. 5 is a perspective view of a second embodiment of
my design;

FIG. 6 is a side elevational view thereof on an enlarged
scale;

FIG. 7 is a front elevational view thereof on an enlarged
scale;

FIG. 8 is a rear elevational view thereof on an enlarged
scale.
